UNITED STATES PATENT OFFICE.

JOHN T. KELLY, OF BUTTE, MONTANA.

WATER SKATE.

Application filed August 23, 1922. Serial No. 583,888.

To all whom it may concern:

Be it known that I, JOHN T. KELLY, a citizen of the United States, residing at Butte, in the county of Silver Bow and 5 State of Montana, have invented a new and useful Water Skate, of which the following is a specification.

This invention relates to a float of novel construction designed for use as a water 10 skate so that, by attaching one of these devices to each foot of the user, it becomes possible for the person to stand on the surface of a body of water and propel himself there-over in substantially the same manner as 15 though skating on the surface of the ground or on ice.

One of the objects of the invention is to provide a structure of this character which is light and durable in construction, can be 20 secured readily to the shoe of the user, and which has means combined therewith for feathering through the water during the forward movement of the skate but which will exert a backward pressure against the 25 water when the skate is subjected to a backward thrust.

Another object is to provide a water skate which, when not in use, can be collapsed and folded so as to occupy the minimum space.

With the foregoing and other objects in view which will appear as the description proceeds, the invention resides in the combination and arrangement of parts and in the details of construction hereinafter described 35 and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a plan view of the device.

Figure 2 is a central, vertical, longitudinal 45 section.

Figure 3 is a section on a reduced scale taken on the line 3—3, Figure 2, parts being broken away.

Figure 4 is a perspective view of one of 50 the paddles.

Figure 5 is a section on line 5—5, Figure 2,

Figure 6 is a section on line 6—6, Figure 2.

Referring to the figures by characters of reference 1 designates the end sections of 55 the keel portion of the device, these sections being hingedly connected as at 2 to the intermediate section 3 of the keel. Hingedly connected to the outer end of each section 1 is an upstanding nose piece 4 preferably 60 hollow, the hinge 5 being so arranged that each nose piece 4 can swing inwardly and downwardly onto the adjacent section 1. Inclined side straps 6 of leather or other suitable material connect the upper ends of these 65 nose pieces to the sides of the sections 1 as shown.

Hingedly connected to the sides of each of the sections 1 are bowed straps 7 preferably 70 formed of metal.

To the sides of each of the bowed strips 7 are connected ears 8 preferably arranged in pairs and similar ears arranged in pairs are secured to the bottoms of the sections 1, as shown at 9. Pivotally mounted between the 75 ears of each pair is an arcuate block 10 provided at one end of a paddle 11. These blocks are preferably so shaped that when the paddles are outstanding, as shown in Figure 2, the inner ends of the blocks will 80 bear against the connections between the ears, thus to hold the paddles against swinging movement in the direction indicated by the arrow in Figure 2. The blocks, by reason of their contours, however, will allow the 85 paddles to swing in the opposite directions, as will be obvious by referring to Figure 2.

Hingedly connected to the upper portions of the bowed strips 7 and the nose piece 4 are telescopically connected top strips 12. 90 The innermost strips 7 are not thus connected, however, but instead, are provided with upstanding brackets 13 and 14 respectively. The bracket 13 has an upwardly extending slot 15 therein in which is adjustably mounted the threaded end of a tie rod 16. The other end of this tie rod is adjustably mounted within a longitudinal slot 17 formed in an angular tongue 18 secured to the top and bottom portions of the bracket 14. The top portion of this tongue forms 100 the toe portion 19 of a foot rest. A plate

20 is secured on the bracket 13 and forms the heel portion of a foot rest. The tie rod 16 has a central eye 21. The ends of the tie rod are adapted to be clamped to the slotted portion by means of nuts 22. Any suitable means may be employed for fastening the toe plate 19 and the heel plate 20 to the shoe of the user. For example an upstanding arcuate flange 23 may be used 10 as a back rest for the heel of the shoe, this flange having a strap 24 extending therefrom for extending over the shoe. Laterally adjustable sole gripping jaws 25 can be slidably connected to the toe plate 18, these 15 jaws being formed with depending portions 26 engaged by an adjusting screw 27 as shown in figure 3. A strap 28 may connect the upstanding sole gripping portions of the jaws and this strap, in turn, can be 20 connected to the strap 24 by a looped strap 29. A slideable heel gripping jaw 30 can be mounted on the heel plate 20, the same being operated by means of a screw 31.

It is to be understood that the means employed for fastening the skate to a shoe does not in itself constitute any part of the present invention as any suitable mechanism for this purpose can be employed. The said shoe gripping means has therefore been 30 shown and described generally rather than specifically.

An air bag 32 is adapted to be arranged along the keel of the skate and is adapted to be surrounded by the arched strips 7, this 35 air bag extending up through the nose pieces 4 as shown in Figures 1 and 2. The air bag has a valve stem 33 projecting loosely through the eye 21.

When the skate is to be used the air bag 40 32 is inflated and will thus hold the keel extended. The toe plate and the heel plate are attached to the shoe of the wearer and it will be obvious that when the skate is moved forwardly relative to the body of 45 water the paddles 11 will feather whereas, when a backward thrust is exerted against the body of water through the skate the paddles will be maintained in outstanding position so as thus to propel the user forwardly. When the skate is not in use the air bags can be deflated and removed after 50 which the tie rods 16 can be disconnected from the slotted portions 15 and 17 and the strap 29 disconnected from the strap 24 or 28. Thereafter the keel can be folded by 55 swinging the members 1 downwardly so as to bring their lower surfaces substantially into parallel relation. The looped or bowed strips 7 can be swung onto the portions 1 of the keel and the nose pieces 4 will also 60 be swung inwardly, thus making a very compact structure that can be carried readily.

What is claimed is:-

1. A device of the class described including a foldable keel, arcuate strips pivotally

connected thereto, nose pieces hingedly connected to the ends of the keel, telescopic connections between said nose pieces and certain of the arcuate strips, adjustable means mounted on certain of said arcuate strips for engaging the heel of a shoe, a float held to the keel and between the nose pieces by said arcuate strips, and paddles pivotally connected to the keel and arcuate strips and mounted to feather. 75

2. A device of the class described including a foldable keel, a float, means bridging the float for connecting it to the keel, feathering paddles upon the keel and connecting means, and means mounted on said connecting means for engagement with the shoe of a user. 80

3. The combination with a foldable keel, nose pieces hingedly connected thereto, and a float removably mounted on the keel and 85 between the nose pieces, of means extending over the float for connecting it to the keel, feathering paddles upon said means and the keel, and means for connecting the float to the shoe of the user. 90

4. The combination with a collapsible keel, and nose pieces hingedly connected thereto, of a detachable float mounted on the keel between the nose pieces, means extending over the float for connecting it to the 95 keel, feathering paddles upon said means and the keel, and adjustable means supported above the float for engaging the shoe of a user.

5. The combination with a collapsible keel 100 and feathering paddles connected thereto, of a float detachably mounted on the keel, feathering paddles supported at the sides thereof, and means supported above the float for attaching the same to the foot of a user. 105

6. The combination with a collapsible keel and nose pieces hingedly connected to the ends thereof, of feathering paddles secured to the keel, a float detachably connected to the keel and between the nose 110 pieces, feathering paddles supported at the sides of the float, and means supported above the float for connecting it to the foot of the user.

7. The combination with a foldable keel 115 and nose pieces hingedly connected to the ends thereof, of bowed strips pivotally connected to the keel, an adjustable connection between the innermost strips, telescopic connections between the remaining strips and 120 the nose pieces, means mounted on the inner strips for connecting the same to the foot of a user, and a float extending under the bowed strips and held thereby to the keel.

8. The combination with a foldable keel 125 and nose pieces hingedly connected to the ends thereof, of bowed strips pivotally connected to the keel, an adjustable connection between the innermost strips, telescopic connections between the remaining strips and 130

the nose pieces, means mounted on the inner strips for connecting the same to the foot of a user, and a float extending under the bowed strips and held thereby to the keel, 5 and feathering paddles connected to the keel and to the bowed strips.

In testimony that I claim the foregoing as

my own, I have hereto affixed my signature in the presence of two witnesses.

JOHN T. KELLY.
